UNITED STATES PATENT OFFICE

FRED C. MYER, OF SACRAMENTO, CALIFORNIA

VENDING MACHINE

Application filed September 9, 1929. Serial No. 391,393.

This invention relates to vending machines and more particularly to spurious coin detectors for coin operated vending machines in which a coin of less value than the one for which the machine is designed may be fraudulently inserted. The primary object of the present invention is to provide means to detect a spurious coin, deflect it to a pocket from which it may be picked up from the outside 10 of the machine, and sound an alarm calling attention to the attempt at fraud.

An important object is the means for using a vertical coin chute in which an adjustable compact anvil is mounted so that a predetermined rebound of a valid coin may be accomplished by adjusting the angle of the anvil to cause the coin to rebound into a chute, from which it travels to the operating mechanism of the vending machine.

20 A particular object of the invention is the mechanical means for retarding and reducing the vibration of a coin as it slides down a chute, whereby each coin of a certain kind will have the same trajectory after striking the same anvil.

It is well known in this art that the vibrations of a coin from side to side as it slides down a smooth chute causes variations in coins in different degrees, for instance, in a 30 new nickel and an old nickel, the trajectory from the anvil will vary.

Even the same coin repeatedly inserted in a smooth chute will vary somewhat in trajectory after striking the anvil.

35 Another object is the provision of a bell in the path of the dropped or rejected coin to sound an alarm for the purpose of making the attempt to use a spurious coin both embarrassing and futile.

40 A further object is to provide means to adjust the height of the chute into which a coin is to be thrown.

Another object of the invention is to provide a resilient surface for coins to strike 45 which are thrown too far so that they will rebound down the short chute and drop out at the bottom.

Other objects will appear to those skilled in the art as the description progresses.

50 In this specification and the accompany-

ing drawings the invention is illustrated in the form considered to be the best, but I do not wish to be understood as confining it to this form because it may be combined in other forms. It is also to be understood that in and by the claims following the description it is desired to cover the invention in whatsoever form it may be embodied.

In the one sheet of drawings

Figure 1 is a sectional view of the coin chute for vending machines showing my improvements therein taken on line 1-1 of Figure 3.

Figure 2 is a sectional view on line 2-2 of Figure 1 showing in dotted lines how the spurious coins strike the bell, and the pocket into which the coins drop.

Figure 3 is an enlarged section on the line 3-3 of Figure 1.

In coin controlled vending machines the coin is generally inserted in a slot near the top of the machine and drops down a chute to the control or release mechanism adjacent the bottom.

The chute may have an incline or curve from front to back, or side to side of the machine. In the present instance the chute 1 is vertical, and a coin inserted at 2 slides down and strikes the anvil 3 which is pivoted on the pin 4 in the chute.

The anvil is held in position and adjusted by the screws 5 and 6.

The anvil has the top surface 7 which is on an angle so that a coin striking it will rebound on a trajectory curve, something like the one indicated by the line 8, into the chute 9 projecting from the main chute.

The angle of the anvil is adjusted so that a certain coin will be thrown far enough to drop into the downwardly depending chute 10 from where it is delivered to the coin control mechanism of the vending machine, which may be any of the well known devices in use for this purpose, but it is preferably used with the coin control device shown and described in my co-pending application of even date. In which event the operating lever is indicated at 11, the projecting member at 12, and the pivoted lever at 13.

Slidable on the plate 14 connecting the

chutes 9 and 10 is mounted the plate 15 which may be adjusted up or down by means of the slot 16 and screw 17.

The top corner 18 of the plate may be adjusted so it is above the bottom point 19 of the chute. The point 19 may be lower than is shown in the drawings if greater adjustment is required.

The adjustment of the plate 15 and the anvil 3 gives quite a wide range of adjustment so that a certain construction of chute can be adjusted to coins of different kind.

A coin not intended for the machine will not be thrown far enough or it will be thrown too far to fall into the chute 10, and will roll back onto the anvil and drop on either side through one of the openings 20 or 21. As the coin drops it strikes the bell 22 and then slides into the pocket 23, where it can be recovered.

The pocket is part of the casing 24 which is attached to the chute by the screws 25 or other suitable means.

The main chute 1 comprises a channel like member 26 and a plate cover 27 secured by screws 28 as shown in Figure 3 in section. Means for causing the coin to slide on the surfaces 29 and 30 consist of plates 31 and 32 in which are set by any suitable means a series of spaced flexible fins 33 and 34 of suitable material.

These fins are designed to offer just enough resistance to the passing coin to hold it lightly against the side and end of the chute.

The plates 31 and 32 are adjustably mounted on the screws 35 and 36 so that the plates may be pressed in, or drawn back to regulate the pressure of the fins on the coin.

The upper end of the chute 9 is open, and a resilient means is mounted in the opening. In this instance a spring 37 is shown secured by the screws 38.

All coins that are thrown too hard strike this spring and rebound back to the anvil.

In the complete operation of the device a coin inserted in the top of the chute drops down and is kept from vibrating as it slides by the flexible fins, which press very lightly on the coin as it passes. The coin strikes the anvil with an impact to cause it to rebound on a trajectory due to the incline of the anvil so that the coin is thrown into the chute leading to the coin control mechanism.

If the coin is of fraudulent weight or material, so that it rebounds too far, it strikes the spring and rebounds back to the anvil and drops out of one of the side openings, and as it drops it strikes the bell and slides into the pocket. If the coin is not thrown far enough, it rolls back down the short chute onto the anvil and out as in the above case.

It will be seen that adjustment is provided for the angle of the impact anvil, for the height of the chute into which a coin is pro-

jected, and for the pressure of the fins on the coin.

Having thus described my invention, what I claim and desire to secure by Letters Patent is:

1. A spurious coin detector for vending machines, comprising a vertical coin chute, a pivoted coin impact anvil in said chute, an opening in said chute adjacent the said anvil, adjusting screws for said anvil, a coin receiving chute above and to one side of said anvil connected to said coin chute, means to adjust the distance of said receiving chute above said anvil and mechanical means to retard a coin dropped in said coin chute.

2. A spurious coin detector for vending machines comprising a vertical coin chute, an adjustable impact anvil having its impact surface at an angle, a coin receiving chute having its receiving end higher than said anvil, means to adjust said receiving end, an opening in said coin chute on each side of said anvil, a bell below said anvil, flexible coin retarding fins in said coin chute, and means to adjust said fins.

3. A spurious coin detector for vending machines, comprising a guideway for coins, an adjustable angle impact anvil in said guideway, an upwardly extending guideway joining said guideway at an angle, a coin receiving chute at the end of said upwardly extending guideway, an adjustable plate between said coin receiving chute and said upwardly extending guideway to control the entrance of a coin to said receiving chute, flexible fins adapted to bear lightly on a coin moving in said coin guideway, and means to adjust the pressure of said fins on the coin.

In testimony whereof I have hereunto set my hand this 5th day of August, A. D. 1929.

FRED C. MYER.
